UNITED STATES PATENT OFFICE.

ROBERT NAYSMITH, OF PITTSBURG, PENNSYLVANIA, ASSIGNOR TO
PITTSBURG TUBE COMPANY, OF PITTSBURG, PENNSYLVANIA, A
CORPORATION OF PENNSYLVANIA.

BED-SPRING FASTENER.

No. 818,187.

Specification of Letters Patent.

Patented April 17, 1906.

Application filed September 27, 1905. Serial No. 280,380.

To all whom it may concern:

Be it known that I, ROBERT NAYSMITH, a citizen of the United States of America, residing at Pittsburg, in the county of Allegheny and State of Pennsylvania, have invented certain new and useful Improvements in Bed-Spring Fasteners, of which the following is a specification, reference being had therein to the accompanying drawings.

This invention relates to certain new and useful improvements in bed-spring fasteners; and the invention relates more particularly to a novel construction used in connection with the manufacture of bed-springs.

The present invention aims to provide positive and reliable means for effecting a perfect holding of a spring woven-wire fabric in a frame, and in this connection I have devised a novel construction which permits of the parts of the frame and its spring woven fabric being easily and quickly assembled and held to maintain a rigid, strong, and durable construction. To this end I have provided a metallic frame for spring woven-wire fabric which will permit of the same being manufactured at a comparatively small cost, and in connection with this construction I have devised novel means for supporting the spring-frame upon a bed.

With the above and other objects in view, which will more readily appear as the nature of the invention is better understood, the same consists in the novel construction, combination, and arrangement of parts, to be hereinafter more fully described and claimed.

The essential features of the present invention are necessarily susceptible to structural changes without departing from the spirit and scope of the invention; but the preferred embodiments are illustrated in the accompanying drawings, in which—

Figure 1 is a top plan view of a spring constructed in accordance with my invention, illustrating the same supported by a bed. Fig. 2 is a sectional view, taken on the line xx of Fig. 1, looking in the direction of the arrow A of said figure. Fig. 3 is a similar view, taken on the line yy of Fig. 1, looking in the direction of the arrow B. Fig. 4 is a sectional view, taken on the line ww of Fig. 1, looking in the direction of the arrow C. Fig. 5 is a perspective view of a malleable casting forming a part of my improved construction.

Fig. 6 is a perspective view of the same looking at the rear side of the casting, and Fig. 7 is a top plan view of the casting.

To put my invention into practice, I employ a construction consisting of four castings 1, two pieces of tubing 2, two angle-bars 3, a webbing of wire 4, or, as it is commonly known, "woven-wire fabric," and numerous rivets or bolts and nuts to secure the parts together.

The castings 1 are identical in construction, and by referring to Figs. 5 to 7, inclusive, it will be observed that the malleable casting consists of a substantially keystone-shaped plate 5, the lower end of which is provided with a tubular extension 6, which is further joined to the plate 5 by a vertically-disposed rib 7, this rib extending from the top of the tubular extension 6 to the top edge of the plate 5. The tubular extension 6 is formed at right angles to the plate 5, and the inner configuration or area of the tubular extension 6 conforms to an oval, as clearly illustrated in Fig. 3 of the drawings. The rear side of the plate 5 is cut away, as at 8, and provided with a transversely-disposed slot 9, the formation of this slot providing a flange 10, the object of which will be presently described. The one side of the plate 5 is provided with a right-angular extension or lug 11. The top of the rib 7 is provided with an upwardly-extending protuberance or pin 12, the object of which will be presently described. Two of each of the castings are joined together by the longitudinally-disposed sections of tubing 2, (illustrated in Fig. 1 of the drawings,) and in cross-section this tubing is preferably formed oval to correspond to the oval opening of the tubular extension 6 of the castings, this construction being employed to prevent the castings from rotating upon the ends of the tubing 2. In practice these sections of tubing form the longitudinally-disposed sides of a frame which supports the web-lace 4.

The angle-bars 3 are adapted to be retained upon the castings 1 by the flange 10 and the protuberances or pins 12 of the castings. The ends of the angle-bars 3 are provided with openings 14, which are adapted to receive the pins 12 of the castings, as clearly illustrated in Fig. 4 of the drawings. The vertical portion of each of the bars 3 when the bars are placed on the castings is

adapted to seat in the slots 9 of said castings and coincide with the plate 5 of each casting. Strips of metal 15 15 are employed for securing the fabric 4 to the bars 3 3, and the edges 5 of the fabric 4 are clamped between the strips 15 15 and the horizontal portion of the angle-bars 3 by a plurality of rivets 16 or the like fastening means, which are placed at intervals along the bars 3 3 to firmly retain the 10 ends of the fabric 4 in engagement with the bars 3 3. The fabric 4 may be made of any desired weave, and I employ a conventional form of woven wire in connection with my improved construction.

15 In assembling the different parts of my improved construction the castings are first placed upon the ends of the tubings 2, these tubings having been cut the proper length to obtain the desired length of bed-spring. The 20 bars 3 3, which have been placed upon the ends of the fabric 4, are now positioned upon the castings, one of said bars being placed in position within the slots 9 9 of the castings and upon the pins 12 12, at which time the 25 opposite end of the fabric is stretched until the bar 3 can be placed in the slots 9 9 of the castings 1 1. In this operation the bar 3 is further retained in engagement with the castings 1 1 by the protuberances or pins 12, 30 which insure a further locking of the bar 3 within the slots 9 of its respective castings. To further insure a positive engagement of the bar 3 with its castings, the ends of the malleable protuberances or pins projecting 35 above the bar can be flattened to form a rivet, which will permanently hold the fabric 4 in a taut condition between the bars 3 3. By this construction it will be observed that a substantially rectangular bed-spring and 40 frame is formed, and in Fig. 1 of the drawings I have illustrated the same in connection with a bed 17. It will be observed that when the spring is positioned upon the bed the right-angular lugs or projections 11 engage 45 the side rails 18 18 of the bed near the foot and head pieces thereof, thus firmly supporting the spring-frame upon the bed.

I desire to call particular attention to the 50 simplicity of the malleable-iron castings and to the manner of fastening the fabric to its frame. By this construction I am enabled to manufacture the castings and their appurtenant parts at a comparatively small cost, and the simple manner in which the different 55 parts of the bed-spring are assembled permits of parts of the bed-spring being shipped or transported in a knocked-down condition, it only being necessary to assemble the different parts when the bed-spring is to be used.

60 I am aware that heretofore it has been the customary practice to use pieces of tubing similar to the tubing 2. It has been the practice to use circular tubing, which was secured in different kinds of castings by keys; but by 65 the construction of the tubing 2 in cross-sec-

tion and the construction of the tubular extensions 6 of the castings it will be observed that the keys heretofore used are dispensed with and that the tubing will be prevented from rotating independently of the cast- 70

It will be apparent from the above description that I have devised a novel form of bed-spring frame adapted to support a fabric. In connection with the castings 75 used I do not care to confine myself to the manner of supporting the same upon a bed-frame, as in some instances the castings may be formed integral with the frame of the bed, which would practically serve the same purpose. The tubular extensions of the castings having oval openings formed therein may be dispensed with and the lower end of each plate provided with an oval opening, this construction being of a more simple 85 form than that illustrated.

What I claim, and desire to secure by Letters Patent, is—

1. The combination with a fabric, of angle-bars secured to the ends of said fabric, 90 castings, each casting consisting of a plate, a tubular extension carried by said plate and having an oval bore, oval tubing adapted to connect some of said castings together, angular extensions carried by said castings and 95 adapted to support said fabric and angle-bars upon a bed-frame, the plates of said castings being cut away at their rear sides and provided with a transversely-disposed slot at the bottom of the cut-away portion to receive the edge of the angle-bar, upwardly-extending pins carried by said plates, said bars having openings formed therein and adapted to receive said pins when mounted upon said castings, substantially as described. 105

2. In a bed-spring, the combination with a woven-wire fabric, of angle-bars secured to the ends of said fabric, strips of metal arranged over the ends of the fabric and riveted to the angle-bars, vertical plates having 110 their rear portion cut away and formed with slots at the bottom of the cut-away portion to receive the lower edges of the angle-bars, said plates having each a pin on its upper edge adapted to pass through a hole in the 115 angle-bar, and a registering hole in the strip carried by the angle-bar and side rails connecting said castings, substantially as described.

3. In a bed-spring, the combination with 120 corner-castings, each consisting of a plate having an integral tubular extension and a rib extending from the tubular extension to the top edge of the plate, said plate being cut away on its rear side and formed with a transverse slot at the base of the cut-away portion, and said plate being provided with a pin on its upper edge and a lug at one side; of the angle-bars adapted to rest on said plates, with one edge in the slot at the rear 125 130

side of the same, the said pins on the plates passing through holes in the said angle-bars, a fabric having its edge attached to the angle-bars and strips riveted to the angle-bars 5 on top of said fabric.

4. A corner-casting for bed-springs comprising a flat plate having a laterally-extending lug, said plate being cut away on one side and provided with a transversely-disposed 10 slot at the bottom of the cut-away portion, a vertically - disposed rib carried by said

plate centrally thereof, a pin carried by the upper end of said rib, and a tubular extension of oval contour carried by the lower end of the plate below said rib. 15

In testimony whereof I affix my signature in the presence of two witnesses.

ROBERT NAYSMITH.
